UNITED STATES PATENT OFFICE.

EDWARD A. MUTH, OF BUFFALO, NEW YORK.

DESIGN FOR A BADGE.

SPECIFICATION forming part of Design No. 30,712, dated May 9, 1899.

Application filed April 11, 1899. Serial No. 712,674. Term of patent 3½ years.

To all whom it may concern:

Be it known that I, EDWARD A. MUTH, a citizen of the United States, residing at Buffalo, in the county of Erie and State of New York, have invented and produced a new and original Design for Badges, of which the following is a specification, reference being had to the accompanying drawing, showing a part thereof.

10 The figure of the drawing is a face view of a badge, showing my design.

As shown in the drawing, the general outline of my design is that of a circular disk upon which is portrayed a bird's-eye view or 15 plan of a city situated along the banks of a lake or river, and arranged above this view is shown a balloon from which a person is just in the act of falling. Space is afforded above and below the picture for any suitable 20 words or dates.

The design consists in the badge, which is disk-shaped in outline, ornamented with an illustration showing a bird's-eye view of a city, a balloon above said city, and a person in the act of falling from said balloon. 25

Having thus described my invention, what I claim, and desire to secure by Letters Patent, is—

The design for a badge as herein shown and described. 30

In testimony whereof I have signed my name to this specification in the presence of two subscribing witnesses.

EDWARD A. MUTH.

Witnesses:

O. E. HODDICK,
R. P. WIGHTMAN.
